CLAIM

The ornamental design for a fin for a cap, as shown and described.

DESCRIPTION

FIG. 1 is a top perspective view of a fin for a cap; FIG. 2 is a front elevational view thereof; FIG. 3 is a rear elevational view thereof; FIG. 4 is a right side elevational view thereof, with the left side elevational view being a mirror image thereof; FIG. 5 is a top plan view thereof; FIG. 6 is a bottom plan view thereof; FIG. 7 is a top perspective view thereof, shown on a cap; FIG. 8 is a rear elevational view thereof, shown on a cap; FIG. 9 is a right side elevational view thereof, shown on a cap; and, FIG. 10 is a top plan view thereof, shown on a cap. The hat outlined by broken lines assists to illustrate the fin for a cap in a position of use and forms no part of the claimed design.

1 Claim, 10 Drawing Sheets
